UNITED STATES PATENT OFFICE.

GEORGE H. STEVENS, OF MELROSE, MASSACHUSETTS.

SHANK-STIFFENER.

SPECIFICATION forming part of Letters Patent No. 434,121, dated August 12, 1890.

Application filed January 23, 1890. Serial No. 337,819. (No model.)

To all whom it may concern:

Be it known that I, GEORGE H. STEVENS, of Melrose, county of Middlesex, State of Massachusetts, have invented certain new and use-

5 ful Improvements in Shank - Stiffeners for Boots or Shoes, of which the following is a specification, reference being had to the drawings accompanying and forming a part here-
of, in which—

10 Figure 1 is a perspective view of my im-
proved shank-stiffener. Fig. 2 is also a per-
spective, showing my improved shank-stiff-
ener attached to a shank-stiffener made from
leather-board or other suitable material. Fig.
15 3 is a vertical lengthwise section of a portion
of a boot, showing the method of applying
my improved shank-stiffener directly to the
sole of the boot or shoe.

My invention relates to shank - stiffeners
20 made from metal. Metallic shank-stiffeners
are well known and are in common use. These
consist, so far as known to me, of a flat strip
of metal having holes usually near either end
25 for convenience in securing the shank-stiff-
ener in place, or the ends of the strip or thin
rod which forms the shank-stiffener are turned
up to form projections, by means of which it
is secured in place. Metallic shank-stiffeners
30 of the first kind mentioned—namely, those
having holes punched in them to receive tacks
or brads—are expensive to use, because in se-
curing them in place the operator is required
35 to handle the tack, put it in position, and
drive it in—an operation which takes consid-
erable time and requires some skill. Metal-
lic shank-stiffeners of the second kind men-
tioned—viz., those which have their ends
40 turned up to form projections by which the
stiffener is secured—are generally applied to
a shank-stiffener made from leather-board or
other suitable material to stiffen the same
and help it when shaped to retain its shape.
These leather-board stiffeners are reversely
45 skived at the toe and heel ends, and as the
projections on the metallic shank should pass
into and through the whole thickness of the
material of the leather-board shank, and not
through the skived end, in order to hold se-
curely, the skived ends of the leather-board
50 shank are unprotected by the metal, and it
often happens that these skived portions,
which project beyond the metallic shank-stiff-

ener, break off. This tendency to break off
is increased by the fact that the stiffener is
weakened at the place where the projection of 55
the metallic shank-stiffener passes through it.

The object of my invention is to produce a
metallic shank-stiffener which may be quickly
and cheaply set in position either in the sole
of a boot or shoe or in a shank-stiffener com- 60
posed of leather-board or other suitable ma-
terial and without the employment of skilled
labor, and, further, to produce a metallic
shank-stiffener which may be nearly as long
as the leather-board stiffener to which it is 65
applied, its ends projecting beyond the points
at which it is secured to the leather-board
stiffener, so as to form for the thin skived
ends of the leather-board stiffener a firm sup- 70
port, and thus prevent said ends from break-
ing; and it consists in a metallic shank of the
kind shown in the accompanying drawings
and hereinafter described.

My invention is simple, and will be readily
understood from the following description. 75

I use, preferably, a tape of malleable iron
of the proper dimensions in cross-section for
the shank-stiffener desired. This I cut in any
well-known manner into sections of the re-
quisite length for a stiffener, and by means of 80
a common punch and die strike up, prefer-
ably, a three-cornered piece *a*, the sides of
which are cut from the strip, but the base of
which is left attached thereto. The projec-
tions *a* are preferably two in number and are 85
some distance inside the ends of the shank,
and are used to secure the stiffener in place.
They are always in position, and the shank is
ready when picked up by the operator to be
placed on the material to which it is to be 90
attached and the projections *a* driven into or
through the material and clinched against a
suitable clinching-surface. The precise width
or thickness or shape of the metallic strip
which forms the shank *b* is unimportant, and 95
may be varied as desired.

When a metal shank is to be applied to a
shank-stiffener of leather-board, I prefer to
make the metal shank sufficiently long to ex-
tend half-way or more across the skived por- 100
tion at the ends of the leather-board shank
d, as shown in Fig. 2, in order that the ends
of the metal shank beyond the securing-points
may afford a support for the thinner skived

portions of the leather-board stiffener. In applying the metallic stiffener to the leather-board stiffener I prefer to place it on the upper surface thereof, as shown in Fig. 2, and 5 to drive the projections *a* through the leather-board and clinch them on the other side. This is done while the stiffeners are flat, and when the stiffener is molded the malleable metal insures the molded stiffener retaining its shape. 10 When the metallic shank-stiffener is applied directly to the insole *f* of a shoe, no other shank-stiffener being used, it is placed underneath the insole and the projections driven home, as shown in Fig. 3. In the latter case 15 the projections *a* should be shorter, so as not to project through the insole, but only into it sufficiently to prevent the stiffener from shifting its position.

My improved stiffener is cheaper to make 20 than any form of metallic stiffener now known

to me, while the ends do not require to be cut down or narrowed or pointed, and thus a broad thin shank may be produced having all the advantages of the well-known perforated shank above referred to, while it has the advantages of ease and cheapness in handling of metallic shanks made with turned-up ends, by which they are secured in place. 25

What I claim is—

A metallic shank-stiffener having securing 30 points or projections inside the ends thereof, said projections being integral therewith and struck up from the metal of which the stiffener is composed, substantially as shown and described.

GEORGE H. STEVENS.
